CLAIM

The ornamental design for a container as shown and described.

DESCRIPTION

FIG. 1 is a front perspective view of a container of a container and lid assembly;

FIG. 2 is a front side view of the container of FIG. 1;

FIG. 3 is a back side view of the container of FIG. 1;

FIG. 4 is a top plan view of the container of FIG. 1;

FIG. 5 is a bottom plan view of the container of FIG. 1;

FIG. 6 is a left side view of the container of FIG. 1; and,

FIG. 7 is a right side view of the container of FIG. 1.

Any portions of the container and lid assembly shown in broken lines depict environmental subject matter only and form no part of the claimed design.
